UNITED STATES PATENT OFFICE.

CLOYD E. LEECH, FRANK O. SEIDELL, AND JOSEPH H. BENSON, OF LIMA, OHIO.

DRIER.

Application filed June 5, 1922. Serial No. 565,800.

To all whom it may concern:

Be it known that we, CLOYD E. LEECH, FRANK O. SEIDELL, and JOSEPH H. BENSON, citizens of the United States, residing at

5 Lima, in the county of Allen and State of Ohio, have invented certain new and useful Improvements in Driers, of which the following is a specification.

This invention relates to driers, and more 10 particularly to drying apparatus in which material to be dried is fed through the apparatus in the opposite direction to the flow of the products of combustion from a furnace.

15 An object of the invention is the provision of a machine in which material is fed through drums in the opposite direction to the flow of heated gases, such as the products of combustion from a fire.

20 A further object is the provision of means for first passing the products of combustion around the drums to heat them and then pass them through the drums.

25 A further object is the provision of means for feeding the material from one drum to another when a plurality of heating drums are employed.

In the accompanying drawings, we have shown one embodiment of the invention.

30 In this showing:

Figure 1 is a vertical sectional view,

Figure 2 is a transverse vertical sectional view on line 2—2 of Figure 1,

35 Figure 3 is a similar view on line 3—3 of Figure 1,

Figure 4 is a similar view on line 4—4 of Figure 1, and,

Figure 5 is a detail view of a cone arranged at the inlet end of each drum.

40 Referring to the drawings, the reference numeral 1 designates generally a casing having a fire box or furnace 2 at the bottom. The furnace may be provided with a suitable grate 3 and fire doors 4 of any desired construction. Bearings 5 are arranged at opposite sides of the machine and are adapted to support shafts 6. A drum 7 is secured to these shafts and adapted to revolve there-

45 with. As shown, one shaft at the outlet end of the drum is provided with a plurality of arms 8, forming a spider to which the drum is secured. The opposite end of the drum is secured to the adjacent shaft by means of arms 9 forming a spider. A cone 10 projects outwardly from the spider to the wall of the casing (see Figure 1) and this

cone is provided with spiral blades 11 which terminate in the arms 9. A second drum 12 is mounted above the drum 7 on shafts 13 which are supported in bearings 14 similar to the bearings 5. The shafts 13 are provided with spiders similar to the spiders arranged at the opposite ends of the shafts 6.

In Figure 1 of the drawings, the shaft to the left is provided with arms 15, forming a spider similar to the arms 8 and these arms are secured to the periphery of the drum. The opposite end of the drum is provided with a cone 16 carried by the shaft 13 and having spiral blades 17. These blades terminate in arms 18 forming a spider. The shafts may be driven in any suitable manner and are connected to each other by gears 19, as shown.

Material to be dried is fed into the machine by means of conveyors 20 having flights 21. The casing is provided with a receiving compartment 22 formed by substantially vertical side walls 23 and a curved wall 24 arranged beneath the cone 16. The vertical walls are provided with hinged doors 25 and shelves 26 are formed on the outside of these doors. Material deposited on the shelf 26 by the conveyor 20 is adapted to open the door 25, then pass over cone 16 to the interior of the drum. Each of the drums is provided with spill plates or stiffeners 27 which extend throughout the length of the drums and are secured to the arms of the spiders.

The casing is provided with an inner housing formed of a curved wall 28 arranged beneath the cone 10 and a vertical wall 29 which is spaced from the wall of the casing. This vertical wall is provided with openings for the ends of the drums and is adapted to permit communication between the upper and lower drums through compartment 30. A stack 31 communicates with the upper drum at its inlet end and an outlet chute 32 communicates with the lower drum at its outlet end.

In operation, material is fed into the upper drum by the conveyors 20 and passes over the revolving cone 16. The blades 17 feed material into the drum 12 where it is agitated by the revolution of the drum and by the plates 27. The material passes from the drum into the compartment 30 and falls upon the cone 10 whence it is delivered to the lower drum. From the lower drum, the material passes to the outlet 32. The prod-

ucts of combustion from the furnace pass up in the casing around the drums, heating the exterior of drums. These products are kept from the compartment 30 by the wall 29 until they flow through the lower drum, then they pass upwardly through the compartment 30 to the upper drum and thence to the stack. By means of the construction disclosed, we provide a construction in which the driest material comes in contact with the hottest and driest gases and is thus thoroughly dried, the gases then passing through the machine in a reverse direction whereby partly saturated gases come in contact with the wetter material. The provision of wall 29 also permits the gases to be passed around the exterior of the drum before entering the lower drum, thus heating the drums and drying any material adjacent the walls.

It is to be understood that the form of our invention herewith shown and described is to be taken as a preferred example of the same, and that various changes in the shape, size, and arrangement of parts may be resorted to without departing from the spirit of the invention or the scope of the subjoined claims.

Having thus described our invention, we claim:

1. In a device of the character described, a casing, shafts extending through the ends of the casing, spiders arranged on the inner ends of the shafts, a drum secured to said spiders, an inlet compartment in said casing adjacent one end of said drum, a cone arranged on one of said shafts within said compartment, and means for delivering heated gases to said drum.

2. In a device of the character described, a casing, a plurality of revolving drums mounted in said casing, a dividing wall in said casing forming a compartment to permit communication between the outlet end of each drum and the inlet end of the next adjacent drum, and means for passing heated gases through said drums.

3. In a device of the character described, a casing, a plurality of revolving drums mounted in said casing, an inlet compartment adjacent one end of one of the drums, receiving compartments arranged between the outlet end of each drum and the inlet end of the next adjacent drum, cones arranged in said inlet compartment and said receiving compartments to deliver material to said drums, and means for passing heated gases through said drums.

4. In a device of the character described, a casing, a pair of revolving drums mounted in said casing, an inlet compartment adjacent one end of one of the drums, a receiving compartment arranged between the other end of said first named drum and the inlet end of the other of said drums, cones arranged in

said inlet compartment and said receiving compartment to deliver material to said drums, means for heating said drums, a stack communicating with said inlet compartment, and means for delivering material to said inlet compartment.

5. In a device of the character described, a casing, a pair of revolving drums mounted in said casing, an inlet compartment adjacent one end of one of the drums, a receiving compartment arranged between the other end of said first named drum and the inlet end of the other of said drums, means for heating said drums, a stack communicating with said inlet compartment, a dividing wall arranged in said casing and separating said heating means from said stack, whereby gases from said heating means are caused to flow from the interior of the drums to the stack, and means for delivering material to said inlet compartments.

6. In a device of the character described, a casing, a pair of revolving drums mounted in said casing, an inlet compartment adjacent one end of one of the drums, a receiving compartment arranged between the other end of said first named drum and the inlet end of the other of said drums, cones arranged in said inlet compartment and said receiving compartment to deliver material to said drums, means for heating said drums, a stack communicating with said inlet compartment, a conveyor tube communicating with said inlet compartment, a conveyor in said tube adapted to feed material to said inlet compartment, and means for normally closing communication between said tube and said inlet compartment.

7. In a device of the character described, a casing, a pair of revolving drums mounted in said casing, an inlet compartment adjacent one end of one of the drums, a receiving compartment arranged between the other end of said first named drum and the inlet end of the other of said drums, cones arranged in said inlet compartment and said receiving compartment to deliver material to said drums, means for heating said drums, a stack communicating with said inlet compartment, a conveyor tube, a partition separating said tube from said inlet compartment, said partition being provided with an opening, a normally closed hinged door covering said opening, and a conveyor in said tube adapted to feed material to said opening, said door being adapted to be opened by material from said conveyor.

In testimony whereof, we affix our signatures in presence of two witnesses.

CLOYD E. LEECH.

FRANK O. SEIDELL.

JOSEPH H. BENSON.
